United States Patent Office

Des. 189,254
Patented Nov. 15, 1960

189,254

PLATE OR SIMILAR ARTICLE

Shigeru Masuda, Nagoya, Prefecture of Aichi, Japan, assignor to Noritake Co., Inc., New York, N.Y., a corporation of New York

Filed Aug. 24, 1959, Ser. No. 57,288

Term of patent 3½ years

(Cl. D44—15)

The figure is a plan view of a plate or similar article, showing my new design.

The plate is of a conventional configuration when viewed from the side and bottom thereof.

I claim:

The ornamental design for a plate or similar article, substantially as shown and described.
